DRAIN DEVICE

Edgar M. Tucker, South Pasadena, Calif., assignor of one-half to W. H. Fabry, Alhambra, Calif.

Application December 6, 1937, Serial No. 178,357

9 Claims. (Cl. 182—1)

This invention relates to drain devices.

The general object of the invention is to provide an improved apparatus for draining areas such as roof areas, etc. particularly in locations where the normal draining operation is likely to be interfered with by debris which clogs the drain.

A more specific object of the invention is to provide a roof drain including a siphon for lowering the water level should the main drain become clogged.

Another object of the invention is to provide a roof drain including a principal drain and an auxiliary drain and wherein a siphon is employed to lower the water level should the drain become clogged.

Other objects and the advantages of my invention will be apparent from the following description taken in connection with the accompanying drawings, wherein:

Fig. 1 is a central sectional view through a drain device embodying the features of my invention;

Fig. 2 is a top plan view of the drain device;

Fig. 3 is a front view of the drain;

Fig. 4 is a fragmentary sectional view through the auxiliary drain member;

Fig. 5 is a view similar to Fig. 1 showing a modification of my invention;

Fig. 6 is a front view showing the modification; and

Fig. 7 is a top plan view of the modification.

In the draining of roof structures where the roof is more or less flat it is customary to provide a drain member so that the water as it falls will be conducted to a suitable outlet.

In a drain device of this nature there is a likelihood of clogging due to leaves and other debris and as a result water accumulates on the roof and its weight seriously damages or in some cases destroys the roof covering or structure. It is accordingly the purpose of my invention to provide a roof drain with an auxiliary drain which will function should the main drain become clogged to lower the water level on the roof.

According to my invention I provide a main drain and an auxiliary drain with a siphon combined with the auxiliary drain and this structure is set forth in the accompanying drawings.

Referring to the drawings by reference characters I have shown my invention as embodied in a drain device which is indicated generally at 10. As shown the device 10 includes a main drain member which comprises a sheet metal base plate 12 having a rectangular aperture 13 there-

in. Furthermore adjacent the edges thereof the base plate 12 has a plurality of apertures 12' therein. Positioned in the aperture 13 I provide a downwardly extending open topped box-like member or well 14, the bottom 15 of which has a circular aperture 16 therein. Around the upper edge the well member 14 includes a flange portion 17 which engages the plate 12 about the periphery of the aperture 13 and is secured thereto as by welding or soldering.

Positioned in the aperture 16 I provide a downwardly extending pipe member 18 having a flanged portion 19 at its upper end which overlays a portion of the well bottom 14 and is secured thereto as by welding or soldering.

Adjacent its lower end the pipe 18 has a threaded collar 20 thereon which may be secured thereto either by welding or soldering. The collar 20 communicates with a drain pipe 20'.

Adjacent one side of the plate 12 I provide an overflow member or auxiliary drain member indicated generally at 21. The overflow member 21 includes a front wall 22, an inclined rear and top wall 23 and end walls 24. The walls 22, 23 and 24 are secured to the base plate 12 as by welding or soldering the lower edges thereto. The front wall 22 adjacent the upper edge thereof has a rectangular aperture 25 therein which is preferably covered by a screen member 26.

As shown in Fig. 4 the screen 26 is preferably removably secured to the wall 22 by clips 27 positioned in suitable apertures 28 in the wall 22 and including a flexible prong 29 which extends through the screen mesh. Below the aperture 25 and intermediate the length thereof the wall 22 has a circular aperture 30 therein.

Within the space covered by the overflow member 21 and intermediate the length thereof the base plate 12 has an aperture 31 therein. Positioned in the aperture 31 I provide a circular conduit member 32. As shown the conduit 32 is positioned at an angle to the base plate 12 and has its lower end opening into the interior of the pipe 18. At its upper end the conduit 32 includes a flanged portion 33 which overlies a portion of the base plate 12 and is secured thereto as by welding or soldering. The conduit 32 where it joins the pipe 18 is secured thereto as by welding or soldering.

Positioned in the conduit 32 I provide a reduced siphon member 34 the upper portion of which extends through the aperture 30 in the wall 22, thence downwardly and terminates in an inlet located adjacent to the plate 12. The lower portion of the siphon 34 is positioned in the pipe 55

18 and extends below the lower end thereof a predetermined distance. The pipe 34 is soldered or welded to the wall 22 and similarly secured to the pipe 18.

5 When the device 10 is installed on a roof the well portion 14 is positioned between a pair of adjacent rafters 35 and the base plate 12 overlies one layer of roofing material 36 on the disk 37. Plastic material 38 is positioned between the 10 plate 12 and the roofing material 36. Plastic material 39 is placed on the base plate 12 and then a sheet of roofing material 40 is laid over the plate 12 up to the flange 17 and firmly pressed in place. The plastic material 38 and 15 39 bonds together through the plate apertures 12' thereby forming a water tight seal.

In Figs. 5, 6 and 7 I show a modification of my invention which is indicated generally at 50. As shown the modification includes a base member 51 from which a principal or main drain member 52 extends downwardly. This main member preferably flares at its upper portion and is provided with a cover 53 which includes a mesh portion 54 which serves to remove the 25 debris carried by the water on the roof.

The main drain 52 communicates with an auxiliary drain indicated generally at 55 and which includes an outlet 56 which enters the main drain. The auxiliary drain includes a 30 cylindrical upper portion 57 which is internally threaded as at 58 to receive an exteriorly threaded pipe 59 in which an elbow 60 is threaded as at 61 for adjustment and is held in adjusted position by a set screw 62 so that the height of 35 the outlet 63 of the elbow relative to the base 59 may be adjusted. Adjacent the elbow I show a siphon indicated generally at 64 and which includes an inlet member 65 which is slidably in a pipe 66 and which may be adjusted by fastening means similar to the means 62 previously described.

The pipe 66 is threaded on the front end of a collar 68 the lower end of which extends downwardly as at 69 forming a siphon member. This 45 member 69 includes an outlet portion 70 disposed within the lower portion of the main drain 52. The lower portion of the main drain 52 is threaded as at 71 to receive a collar 72 by means of which an outlet pipe 73 is coupled to 50 the drain.

The device shown in Figs. 1 to 4 inclusive is preferably made of sheet metal while the device shown in Figs. 5, 6 and 7 is preferably an aluminum or iron casting although the particular 55 manner in which these parts are made forms no part of the present invention.

In the operation of the two devices the water enters the main drain and flows therethrough so long as this drain is not clogged. Should the 60 main drain become clogged the water level will rise and enter the inlet to the siphon and a small portion of the water will pass through the siphon as soon as the water level rises above the top of the elbow in the siphon.

65 As soon as the water level rises to the inlet to the auxiliary drain the water will pass through this drain and will drain the roof so long as the rain continues. Since the debris collects about the principal outlet there is practically no likelihood of the auxiliary outlet being clogged. As soon as the source of water such as the rain has ceased the action of the siphon continues 70 until the water level is below the inlet to the siphon. Consequently there is no danger of the weight of water on the roof becoming so heavy

as to injure the roof covering or the structure which supports the roof.

From the foregoing description it will be apparent that I have invented a novel drain device which can be economically manufactured and which is highly efficient for its intended purpose.

Having thus described my invention I claim:

1. In a drain device, a main drain member having an inlet and outlet, an auxiliary drain member, said auxiliary member including an inlet 10 and a conduit extending to said outlet, a siphon member independent of said main drain member and said auxiliary drain member and having its inlet disposed above said main drain member inlet and below said auxiliary drain member inlet, said siphon member having an outlet.

2. In a drain device, a main drain member having an inlet and outlet, an auxiliary drain member, said auxiliary member including an inlet remote from said main drain inlet and a conduit extending to said outlet, a siphon member having its inlet disposed below said auxiliary drain member inlet and remote from the main drain inlet and the auxiliary drain inlet, said siphon member having its outlet end opening 25 into said drain member outlet.

3. In a drain device, a drain member having an outlet, an overflow member, said overflow member including an inlet and a conduit extending to said outlet, a siphon member independent of said drain member and said overflow member and having its inlet disposed above said drain member, said siphon member having its outlet end opening into said drain member.

4. In a drain device, a main drain member 35 having an inlet and an outlet, an auxiliary drain member having an inlet disposed above the main inlet, said auxiliary drain having an outlet communicating with the main drain outlet and a siphon member independent of said main drain 40 member and said auxiliary drain member and having an inlet disposed below said auxiliary drain inlet, said siphon member having an outlet.

5. In a drain device, a base plate having an 45 opening therein, a receptacle beneath said opening, said receptacle having an aperture in the bottom thereof, a pipe member in said aperture, an overflow member on said base plate, said overflow member including a front and a 50 rear wall and end walls, the upper edge of said overflow member including an aperture, and a conduit extending from the bottom of said overflow member to said pipe to afford communication between the overflow member and the pipe.

6. In a drain device, a base plate having a rectangular opening therein, a receptacle having edge flanges thereon engaging the lower surface of said base plate about said aperture, said receptacle having a bottom with an aperture therein, a pipe member in said aperture, said pipe member having a flange engaging the bottom of the receptacle, a threaded collar engaging said pipe, a coupling engaging the threaded collar, an overflow member on said base plate, said overflow member including front, rear and end walls, the front of said overflow member including an aperture, a screen covering said aperture and a conduit extending from the bottom of said overflow member to said pipe to afford communication between the overflow member and the pipe.

7. In a drain device, a base plate having an opening therein, a receptacle beneath said opening, said receptacle having an aperture in the

bottom thereof, a pipe member in said aperture, an overflow member on said base plate, said overflow member including a front and a rear wall and end walls, the upper edge of said overflow member including an aperture, a conduit extending from the bottom of said overflow member to said pipe to afford communication between the overflow member and the pipe, a syphon member having its upper end extending 10 through the front wall of said overflow member and terminating near the top of said base member, said syphon member having its other end portion extending through said conduit.

8. In a drain device, a base plate having a rectangular opening therein, a receptacle having edge flanges thereon engaging the lower surface of said base plate about said aperture, said receptacle having a bottom with an aperture therein, a pipe member in said aperture, said pipe member having a flange engaging the bottom of the receptacle, a threaded collar engaging said pipe, a coupling engaging the threaded collar, an overflow member on said base plate, said overflow member including front, rear and 25 end walls, the front of said overflow member

including an aperture, a screen covering said aperture, a conduit extending from the bottom of said overflow member to said pipe to afford communication between the overflow member and the pipe, a syphon member having its upper end extending through the front wall of said overflow member and downwardly directed and terminating near the top of said base plate, said syphon member having its other end extending 10 through said conduit and into said pipe.

9. In a drain device, a main drain member including a pipe having an inlet and an outlet, a closure for said inlet, an auxiliary drain device including an inlet and an outlet, said auxiliary drain device being disposed without said main drain member and having its outlet communicating with the main drain member outlet, an adjustable syphon member having its upper end disposed adjacent to the auxiliary 20 drain device and terminating below the main drain inlet, said syphon member having its lower end extending into said main drain member outlet.
